UNITED STATES PATENT OFFICE.

FRITZ C. LUCKE D'AIX, OF NEW YORK, N. Y.

TYPOGRAPHIC MACHINE.

1,062,770.

Specification of Letters Patent. Patented May 27, 1913.

Application filed November 14, 1908. Serial No. 462,670.

To all whom it may concern:

Be it known that I, FRITZ C. LUCKE D'AIX, a citizen of the United States, residing in the borough of Brooklyn, city and State of New York, have invented certain new and useful Improvements in Typographic Machines, of which the following is a specification.

The invention relates to typographic machines, and more particularly to machines which cast characters and designs from molten metal.

Objects of the invention are to provide a machine which will rapidly cast successive types or line slugs either from the same matrix or matrices or from different matrices; to provide for setting different sizes, sorts and other varieties of types and designs by hand for casting while the machine is casting different types or a different line; to provide for rapid and easy manual control of the casting as to the number of casts made, or as to what types or lines are successively cast; to provide for rapid and certain accommodation of the operative parts of the machine for different sizes of line without dismantling or disorganizing the mechanisms and practically without delaying the operation of the machine; to provide for improved operation of the parts so as to secure slugs and other castings of excellent quality; to provide a machine embodying the features enumerated, which is of simple, substantial and economical design and efficient operation. These and other objects of invention will in part be obvious and will in part more fully appear herein.

The invention consists in the novel parts, arrangements, constructions, combinations and improvements herein shown and described.

The accompanying drawings, referred to herein and forming a part thereof, illustrate one embodiment of the invention, the same serving in connection with the description herein to explain the principles of the invention.

In the drawings Figure 1 is a front elevation of a machine constructed in part in accordance with the principles of the invention. Fig. 2 is a right hand elevation corresponding to Fig. 1, showing the mold and mold carrier in section. Fig. 3 is a rear elevation corresponding generally to Fig. 1. Fig. 4 is a vertical section on the line A—B

of Fig. 5. Fig. 5 is a top plan view corresponding substantially to Fig. 1. Fig. 6 is a front view of the mold, mold carrier and cooperating parts. Fig. 7 is a right hand elevation corresponding generally to Fig. 6. Fig. 8 is a detail of one end of the mold showing the trimming knives. Fig. 9 is a view on the line C—D of Fig. 8. Fig. 10 is a top plan corresponding generally to Fig. 8, with upper mold jaws removed. Fig. 11 is a detail elevation of the carrier for the matrix lines. Fig. 12 is a section on the line E—F of Fig. 11, looking to the left. Fig. 13 shows the carrier for the matrix lines and the mold co-operating in the casting position, and Figs. 14 and 15 show a form of cast slug or letter.

In the embodiment of the invention illustrated in the accompanying drawings, a matrix carrier 1 is shown and according to certain features of the invention, said carrier is provided with a plurality of means for holding a line of matrices, and is constructed and arranged so as to present any of the lines of matrices at the casting position. In certain of its aspects the invention provides a carrier and the line holding means and associated parts constructed and arranged so that while one line is in position for casting, another line holding means is in position to receive or discharge its line of matrices. As shown herein, the carrier 1 is rotatably mounted in a suitable manner, as upon a shaft 2 carried by the machine frame, and is shown by way of example provided with means for carrying four lines of matrices. These are so arranged upon the carrier that when one line holding means is at casting position, another is in front of the operator so that a line of matrices can be slid into or out therefrom. By further way of illustration, and referring particularly to Fig. 13, the holding means for the lines of matrices may be of different forms, which need not be described in detail herein. The matrix carrier 1 is shown operable by the operator so as to present any desired one of the lines of matrices at the casting point. For this purpose, in the present embodiment of the invention, it is provided with a suitable pawl and ratchet mechanism 3, mounted at one end and having a handle 4 for operating same. Means are also provided for locating a line of matrices at the mold face and in alignment with the mold slot for cast-

ing. The form thereof, herein shown, comprises a disk 5 having notches 6 therein, and positioned to co-act with the notches 6 and disk 5 is shown a spring-pressed detent 7, shaped so as to center the carrier accurately when the detent engages the notches, the notches being suitably located with respect to the various holding means for the matrix lines upon the carrier 1.

10 A suitable mold for casting the slug or linotype is provided and according to certain features of the invention such mold is provided with jaws movable to give different dimensions of slot widths and lengths as desired. Means for causing movement of the jaws to so vary the slot are also provided, and are also shown acting automatically thereon under the control of suitable setting devices which may be set by the operator to give the width and length desired to the mold slot.

The mold is shown herein mounted in a suitable carrier 8. Relative movement between the matrix carrier and the mold is provided so that the matrix or matrices can close the face of the mold during the casting operation and in this embodiment the mold is shown movable toward the matrix carrier 1. The mold carrier 8 is shown for this purpose slidably mounted upon guides 9 carried upon the machine frame. Any suitable means for so sliding the mold may be provided, and in the illustrated form there is shown connected to the carrier 8, a lever 10, suitably pivoted upon the frame of the machine, the other end 11 of said lever being in operative relation with a suitable cam 12, being held to the cam by a spring 13. The mold is also adapted to carry the slug from casting to ejecting position for the ejection of the cast slug, and then to return to casting position. For this purpose and in the embodiment illustrated herein, those parts of the mold which reciprocate between casting and ejecting position are mounted in a slide 14, carried by and longitudinally reciprocable in the carrier 8, being properly guided in its movements therein by guide keys 15. For the purpose of giving the desired reciprocatory movement thereto between the casting and ejecting positions, means are provided of any suitable or convenient form and are shown herein as comprising a lever 16 pivoted upon the frame 55 of the machine at 17 and having its free end working between pins 18 carried upon the slide 14. The said lever is shown in operative relation with a rim cam 19 by means of suitable anti-friction rolls 20. The said cam, it will be understood, is suitably shaped so as to give the necessary dwell to the slide in the casting and ejecting positions.

The particular embodiment of adjustable mold shown in the illustrated embodiment, 65 has jaws 21 and 22, and end pieces 23 and 24

constituting the walls of the mold cavity or slot. The jaw 21 and end piece 24 are mounted in and move with the slide 14. The jaw 21 is movable vertically, referring especially to Figs. 6 and 13 of the drawings, in the slide 14 and the end piece 24 is carried thereby and is slidable in a slotted recess therein. A spring 25 acts on the piece 24 to keep it in close contact with the jaw 22, said spring being shown herein as a coiled spring arranged around a pin 26 fixed to the piece 24. The end piece 23 is connected to the jaw 22 but is free to move transversely thereto and transversely to the width of the slot, and a spring is provided for keeping the end piece 23 in contact with the jaw 21. The said spring is shown herein as a bow spring 27. The lower jaw 22, together with its end piece 23, are connected to the mold carrier 8, and do not participate in the reciprocating movement of the slide 14. The jaw 22, as hereinafter more particularly described, is susceptible of lengthwise adjustment relatively to the upper jaw in order to correspondingly vary the position of the end piece which it carries, and thus to determine the length of the mold slot.

The jaw 21 is shown, referring more particularly to Fig. 6, fixed to a retaining piece 29 having its opposite face inclined, as shown at 30 in Fig. 6. Mounted in the slide 14 to slide lengthwise thereof is a controlling piece 31. The said piece has a surface of corresponding inclination to the surface 30 resting in contact therewith. It will thus be seen that movement of the controlling piece 31 will determine the position of the jaw 21 relative to the jaw 22 to govern the width of the mold slot. Suitable devices are provided for governing the movement of the controlling piece 31 and in the illustrated form thereof a pin 32 is shown extending in one direction and a corresponding pin 33 in the opposite direction. A suitable stop 34 is provided for engaging the pin 32 as the mold moves toward the casting position, and, the controlling piece 31 being thereby brought to rest, the continued travel of the mold serves to move the jaw 21 toward the jaw 22 against the pressure of the springs 25 and 27 to give a slot of the desired width at the casting position. The stop 34 is adjustable so as to govern the relative movement between the controlling piece 31 and the piece 29 for the purpose of varying the width of the slot. A suitable stop 35 is provided for engaging the rod 33 as the mold moves to the ejecting position thereby moving the controlling piece 31 in the opposite direction and thus allowing the jaw 21 to recede from the jaw 22 under the action of the spring 25. It will be understood therefore that while the relative position of the controlling piece 31 and the retaining piece 29 determine the width of the slot, the periodic 130

movement of the controlling piece 31, as described, serves to bring the mold to width for casting and to open it for the ejection of the slug. As shown herein the stops 34 and 5 35 are parts of a bar 26 mounted upon standards 37 fixed with respect to the carrier 8. The said bar is shown provided with slots 38 through which pass clamping screws 39. If desired, means for further securing the 10 bar 26 in position may be employed and a form of such means is shown herein comprising a series of apertures 40 in the bar 36, there being a corresponding series of apertures in the mold carrier 8, a pin 41 passing through two of these apertures in 15 register serving to secure a bar 36 against displacement by impact of the rods 32 and 33 against their respective stops.

The jaw 22, as hereinbefore said, is attached to the mold carrier 8. It is attached to the carrier through the intermediary of a support 42, which rests in an undercut recess in the top of the lower longitudinal limb of the slide 14, as shown in Fig. 13, a 20 retaining plate 43 on the front of the slide 12 overlapping the front of the support 42, and assuring these parts in operative position relatively to one another. Support 42 is secured to the carrier 8, by a bracket 45 25 on the front of the carrier, to which bracket the support is secured by a bolt or clamping screw 47 which passes through the support 42 and a slot 46 in the top of the bracket 45. In order to permit the longitudinal adjustment of the support 42, and consequently of the lower jaw 22, which it carries, necessary to vary the length of the mold slot, there is formed in the support 42 a longitudinal slot 44 through which the bolt 30 or clamping screw passes. If the screw be loosened, the support 42, together with the lower jaw 22 and end piece 23, which it carries, can be moved lengthwise, until the desired adjustment has been effected, after 35 which, by tightening the screw, the parts can be secured in their adjusted position.

In the reciprocation of the slide 14 between casting and ejecting positions, the upper jaw 21 and front end piece 24 move 40 with said slide, while the lower jaw 22 and rear end piece remain at rest. The cast slug which is carried by the upper jaw from casting to ejecting position must therefore move over the face of the lower jaw, and 45 for this reason the lower jaw, as shown, is of length to extend from ejecting to casting position. In order to thus move the cast slug, suitable means are provided consisting in the present instance of suitable lugs on 50 the under or casting face of the upper jaw 21 as shown in Fig. 6, the intervals between which at the time of casting the slug are filled by the type metal, to form lugs by 55 which the slug is carried along by the upper 60 jaw when the latter subsequently moves

from casting to ejecting position, the slug during this movement sliding along over the lower jaw 22. The general form of the slug is shown in Fig. 14. By the time the slug reaches ejecting position the jaw 21 has 70 been lifted away from it far enough to be disengaged from the lugs on the top of the slug, leaving it free to be expelled by the ejector.

The end piece 23 bears on its upper face 75 against a block 49 slidably mounted upon the rods 50 carried upon the carrier 8. The block 49 is shown provided with an inclined surface 51 against which contacts a roll 52 carried upon arms 53 fixed with reference to the jaw 21. It will be understood that as the mold comes to casting position the roll 52 will travel along the inclined surface 51 thus depressing the block 49 and consequently moving the end piece 23 against its 80 spring 27 to bring it into exact alinement against the jaw 21 for the casting operation.

Suitable devices for trimming the slug are provided, the form thereof herein shown comprising a slotted guide plate 54 mounted upon the carrier 8 in which is mounted a block 55 fixed to an arm 56 passing around a threaded rod 57 provided with adjusting nuts 58 to which the arm 56 is yieldingly held by a spring 59. Mounted upon the block 55 is a trimming knife 60 to shave or trim the front face of the cast bar along its upper edge for the purpose of removing therefrom any rib or fin remaining from casting. A knife 61 is also shown mounted upon the carrier frame in position to act against the front face of the cast bar at its lower edge. A suitable knife 62 is also mounted upon the carriage for the purpose of trimming the side face of the slug to 100 bring it to the proper thickness, and a knife 63 for trimming off the sprue from the bottom side of the slug to bring it to the proper height and to have the bottom face parallel to the character face.

Suitable ejecting means are provided. According to certain features of the invention ejecting means are provided to coöperate with a mold giving different dimensions of slot for casting as desired, such ejecting means automatically accommodating itself to the size of the slot. In the accompanying embodiment therefore a form of such ejecting means is shown. The ejector is shown as comprising a plurality of slug engaging elements 64 arranged in alinement with the mold at the ejecting position. Suitable moving means for the ejector are provided and in the illustrated form thereof moving means for each separate slug engaging element are provided shown herein as comprising a series of bell crank levers 65 suitably pivoted upon the machine frame, an end of each lever engaging with one of the slug engaging elements 64 and the other end of 115 120 125 130

each of said levers 65 bearing on a contact piece carried by the arm 66 which is in operative relation with a suitable cam 67. The said levers are caused to follow their cams by suitable means such as springs 68. By a construction such as shown and described it will be understood that, when permitted by the cam the spring 68 will act upon the levers 65 to move forward the slug engaging elements 64. Such of these elements as are in alinement with the slot will engage the slug and eject it from the slot. Should any of the elements 64 not be in alinement with the slot, as might be the case especially in the form of mold wherein both jaws move out to the ejecting position, they would come in contact with the back of the mold and be arrested thereby. As the cam rotates, all the ejector elements would be restored to their inactive position by their levers.

Receiving means for the ejected slugs are shown herein and the illustrated form thereof comprises a galley 69 provided with a suitable block 70. Attached to the said block is shown a weight 71 carried by a cord 72. A suitable pawl and ratchet mechanism 73 is provided for holding the block in position against the pull of the weight 71. Mounted above the galley is shown a presser bar 74 slidably mounted upon rods 75 carried by the carrier 8. The said presser bar is connected by pivoted links 76 and crank arms 77 to a shaft 78. Fixed to said shaft is a crank arm 79 connected by a link 80 to a bell crank lever 81. Said bell crank is connected with a rod 82, the other end of which is in operative relation with a cam 83. Through the action of the train of mechanism described the presser bar serves to press the slugs as delivered into the galley, the block 70 feeding downward as the slugs are pressed into the galley, and being held in each position by the pawl 73.

Suitable means are provided for supplying molten metal to the mold, and the form thereof shown herewith comprises a melting pot 84 shown with shoes 85 resting on trunnions 86 carried on the machine frame. In the present embodiment this melting pot is moved to and fro into and out of operative relation with the mold and suitable means are provided for so moving the melting pot, the illustrated form thereof comprising a lever 87 pivoted upon the machine frame and having one end in operative relation with a suitably shaped cam 88 and its other end bifurcated and straddling a pin 89 fixed to the melting pot 84. Slidably mounted upon the rod 89 is a sleeve and washer 90 and between the washer and the melting pot a suitable spring 91. The nut and washer 92 are also shown on the end of the rod 89 for keeping the forked end of the lever 87 in position. It will be understood that these connections will give a yielding action and

serve to press the nozzle of the melting pot into close contact with the mold in casting operation. Through an aperture in the cover 93 of the melting pot, works a piston 94 one end of which is connected to the piston plunger 95 and the other end to the arm 96 fast on the shaft 97. Fast also upon the shaft 97 is shown an arm 98 to the end of which is pivoted a link 99 connecting the arm 98 with a lever 100 pivoted to the machine frame and being in operative relation through an anti-friction roll 101 with a suitable cam 102. The lever 100 is acted upon by a spring 103 which serves to hold it to its cam.

The invention in one of its aspects provides for a plunger action which will promote and effectuate the production of solid slugs, such as are necessary for good work and are at the same time difficult for production. Means are provided therefore for allowing a slow and gradual return of the piston after its ejecting stroke so that there may be no back suction to draw the still warm metal from the interior and back parts of the slug where it is still hot when the outer parts have cooled more and consequently solidified. The illustrated form of such means comprises a pin and slot joint 104 between the link 99 and lever 100 (see Figs. 2 and 4). Fixed to the shaft 97 is shown an arm 105, to which is attached a spring 106, attached also to the machine frame at 107. This spring is adjusted so as to give the desired return motion to the plunger 95, after the cam 102 has removed the pressure of the spring 103, the lever 100 at this time moving independently of the link 99, by reason of the pin and slot connection 104.

Suitable means are provided for varying the tension on the spring 103 and the illustrated form thereof comprises an arm 108 fixed on a shaft 109 which has also fixed thereon a ratchet 110 with which a pawl 111 operates. A hand lever 112 is also fixed to the said shaft. Said devices provide for varying the tension on the spring 103 as may be desired to meet the varied conditions of casting. Thus a close control of the movement of the plunger 95 in both directions and consequently of the action of the metal in the mold is secured.

Suitable driving and controlling means are provided and in this embodiment the various cams are conveniently mounted upon a shaft 113 carried in the machine frame and connected by a gear 114 and intermediates 115 and 116 with a pinion 117 on a shaft 118 which shaft has loosely mounted thereon a driving pulley 119. Bearing on the inner face of the pulley 119 are movable shoes 120 carried upon rods 121 connected in suitable bearings 122 carried on a spider 123 fixed to the shaft 118.

Links 124 are pivoted to the rods 121 and to a groove collar 125 slidably mounted upon the shaft 118.

Engaging the collar 125 so as to move it to and fro to cause the shoes 120 to move into and out of contact with the driving pulley 119 is a bifurcated lever 126 having its other end fixed upon a shaft 127. To the shaft 127 is fixed an arm 128 having a spring latch handle 129 adapted to engage apertures 130 in the plate 131 to hold the device in either the operative or inoperative position with respect to the driving pulley. The said latch is constructed so as 15 to be held out of operative relation when desired, so that the handle may move freely, when it is desired to have the machine governed by other of the controlling devices described herein. This device furnishes a 20 form of hand-operated means for throwing the power on and off. A suitable pedal connection is also provided for throwing off the machine, and a form thereof herein shown comprises a rod 132 pivoted to the 25 lever 126 and under impulsion from a spring 133, said rod 132 being slidably mounted in suitable bearings on the machine frame. A bearing plate 134 is shown at the other end of said rod serving to hold 30 it in position against impulsion of its spring, said plate being suitably pivoted upon the frame of the machine. Connected to said plate is an arm 135 to which is pivoted a link 136 connecting it to the pedal lever 137. 35 A spring 138 acts to return the lever 137 to inoperative position. Suitable devices for automatically throwing out the machine after the casting of each slug are also provided and the illustrated form thereof comprises 40 an arm 139 fixed to the plate 134 and extending into the path of a trip 140 carried by one of the cams upon the shaft 113. A hook 141 is shown which may be moved by its handle 142 into and out of position to 45 engage the arm 98 to stop the plunger action and thus prevent casting without throwing out the machine.

The manner of operation of the herein-described machine will be clearly understood by those skilled in the art from the foregoing description, but a résumé thereof will be appended hereto. A line of matrices may be fed into one of the matrix line carriers of the carrier 1. The operator 55 then by means of the handle 4 rotates the carrier 1 upon its shaft 2 until the line is in the casting position, as shown in Fig. 13 of the drawings. As the mold approaches the casting position, the controlling piece 31 60 will be positioned by its rod 32 contacting with the stop 34, the further travel of the jaw 21 then serving to press it toward the jaw 22 to give the predetermined size to the slot, in the manner hereinbefore described. The contact piece 52 during the

said movement has ridden upon the inclined surface 51 and the block 49 (see Fig. 6) has moved the end piece 23 against its spring so as to bring it accurately to fill the slot end between the jaws 21 and 22. The mold carrier 8 is moved toward the matrix line, sliding along the guides 9 under actuation of the lever 10. The pot 84 is moved forward until the nozzle is against the mold (see Fig. 2), whereupon the plunger action takes place in the manner hereinbefore described. After the plunger has been withdrawn and the melting pot has receded, the mold is moved backwardly a very slight distance. The carriage 14 then slides upon the mold carrier 8 toward the ejecting position as hereinbefore described, the carriage 14 takes with it the upper jaw 21 and end piece 24, the slug sliding upon the surface of the lower jaw. On approaching the ejecting position the stop 35 acting on the rod 33 brings the controlling piece 31 to rest, whereupon the jaw 21, under impulsion of the spring 25 moves away from the slug. The ejector then pushes out the slug 90 into the gallery 69, the presser bar 74 pushing on the slug, the follower 70 feeds down the thickness of the slug and is held in that position by its pawl and ratchet.

If the handle 128 is left free to move, the arm 139 will trip the machine once for every slug cast, but if the handle 28 is locked in the operative position it will be seen that the arm 139 will not throw out the machine. The plate 134 will be moved from in front of the rod 132, but the spring 133 will be kept from acting. The pedal 137 will serve to throw out the mechanism at any part of the cycle of operations when the handle 128 is not in the operative position. It will be seen that while one line of matrices is cast another line may be removed from the carrier or inserted therein, that any desired line may be moved to the casting position and that any number of slugs may be cast from any line of matrices. No description of the operation of the minor parts is necessary.

From all the foregoing it will be understood that a mechanism has been provided embodying the principles of the invention and realizing the objects of the invention and the advantages herein set forth together with other objects and advantages.

The invention, in its broader aspects, is not limited to the particular constructions shown, nor to any particular constructions by which it has been or may be carried into effect, as many changes may be made in the construction without departing from the main principles of the invention and without sacrificing its chief advantages.

I do not here claim the mold and ejecting devices, the same having been made the subject of my application, Serial No. 757,347, 130

filed March 28, 1913, as a division of this application. But

What I do claim as my invention and desire to secure by Letters Patent is:—

- 5 1. A typographic machine including in combination a mold and a rotatable matrix carrier permanently located in the frame of the machine at the casting point and having means for holding a plurality of lines of matrices, and manually operated means for causing said carrier to present at will any selected one of the several lines of matrices, which it carries, to the mold.
- 10 2. A typographic machine including in combination a mold and a rotatable matrix carrier permanently located in the frame of the machine at the casting point and having means for holding a plurality of lines of matrices, manually operated means for causing said carrier to present at will any selected one of the several lines of matrices which it carries to the mold and means act-

ing to automatically align the selected line of matrices with the mold slot.

- 25 3. A typographic machine including in combination a mold movable between casting position and ejecting position, a melting pot, an automatically operated ejector, and a rotatable matrix carrier permanently located in the frame of the machine at the casting point and having means for holding a plurality of lines of matrices, said matrix carrier being rotatable at the will of the operator to present any selected one of the several lines of matrices which it carries, to the mold.

In testimony whereof, I have signed my name to this specification, in the presence of two subscribing witnesses.

FRITZ C. LUCKE D'AIX.
